DESIGN FOR AN ALPHABET FOR FORMING MONOGRAMS OR SIMILAR ARTICLES

Michael Chernow, New York, N. Y.

Application March 17, 1941, Serial No. 99,648

Term of patent 14 years

To all whom it may concern:

Be it known that I, Michael Chernow, a citizen of the United States and residing at New York, in the county of New York and State of New York, have invented a new, original, and ornamental Design for an Alphabet for Forming Monograms or Similar Articles, of which the following is a specification, reference being had to the accompanying drawing, forming part thereof, and in which—

Fig. 1 is a plan view of the alphabet showing my new design, and,

Fig. 2 is a perspective view of one of the letters of the alphabet, namely the letter (H).

I claim:

The ornamental design for an alphabet for forming monograms or similar articles, substantially as shown.

MICHAEL CHERNOW.
